WINDOW FRAME CONSTRUCTION

Axel W. Anderberg, Los Angeles, and Wilbur F. Blakemore, Beverly Hills, Calif., assignors to A. W. Anderberg Manufacturing Co., Los Angeles, Calif., a corporation of California

Application March 10, 1953, Serial No. 341,507

12 Claims. (Cl. 20—12)

The present invention relates generally to improvements in the design and construction of window frames; and more especially to frames for sliding sash having a spring-type balance incorporated in the window frame in order to balance the weight of each individual sash. The invention is also particularly concerned with improvements in the design and construction of the parting bead for the window frame.

It is conventional practice to place a spring-type sash balance in the jamb of a window frame in order to balance the weight of the two vertically sliding sashes, windows of this type being commonly referred to as "double hung." The sash balance is ordinarily set into the jamb by providing the jamb with a recess of suitable size to receive the balance with the surface of the face plate on the sash balance substantially flush with the exposed inside surface of the window frame. This permits each sash to slide up and down within the frame and pass over the sash balance with a relatively close fit. In the ordinary double-hung window there are two sashes within the frame; and these are guided at one side by a vertical parting bead which is a narrow strip of wood mounted on the jamb of the frame, usually by being set into a groove in the jamb. On the side jambs of the frame this parting bead lies between the two sashes; it forms the inside guiding surface for the outer sash and the outside guiding surface of the inner sash. In conventional practice, the parting bead is continuous from the top to the bottom of the frame and is notched or cut away to a reduced height where it passes over the sash balance. The parting bead is often broken in the process of notching it because of the reduction in cross section. Unless the grain of the wood lies in a direction that is favorable to notching, a wood parting bead is frequently broken and is consequently discarded, since, as mentioned above, it is the usual practice to make the parting bead a single continuous member throughout its length.

A considerable amount of time is required for a workman to properly notch a parting bead for this purpose, although the operation is essentially a simple one. If the job is not carefully done it may have to be done over again because of excessive clearance between the bead and the sash balance through which air can pass; and even with the exercise of care in fitting and cutting, it is not always possible to eliminate completely such air leakage. For this reason it has not been practical to weatherstrip double hung windows using a spring-type sash balance; and therefore the use of this balance is looked upon with disfavor in colder climates where weatherstripping of the windows is desired.

Another marked disadvantage of the conventional construction is found when it becomes necessary to remove a sash balance from the window frame for any reason, as for example, when a spring breaks and a new unit is required as a replacement for the old one. Because the parting strip in the conventional construction is continuous and passes over the sash balance, it is neces-

5 sary to remove the parting strip from the window frame as a preliminary step to removing the sash balance. In turn, this can be accomplished only by first removing the trim molding inside the frame and then taking the inner sash out of the frame. Even though this may not be a particularly difficult operation, yet it requires considerable care and time to remove the molding from the window without irreparably scarring and damaging the frame; and even with the greatest of care, it is usually 10 necessary to repaint the entire window frame and trim in order to remove signs of the repair work.

Thus it is a general object of our invention to modify the conventional type of parting bead in a window frame for double hung sash to eliminate time and labor spent 15 in fitting the bead over a sash balance and to make for easier removal of the bead to the extent necessary to permit removal of the balance from the window frame.

It is also an object of our invention to provide a novel construction of a window frame having a spring-type sash 20 balance in the jamb and a parting bead extending across the sash balance such that the parting bead can be removed to permit removal of the sash balance without requiring removal of either sash from the frame.

It is also an object of our invention to provide a 25 novel construction of a window frame and parting bead such that there is no air leakage around the parting bead where it passes over a sash balance, thus simplifying the problem of weatherstripping the sliding sash in the frame.

These and other objects of our invention have been 30 attained in a window frame having a recess in the jamb and a spring-type sash balance set into the recess by dividing the parting bead into three separate pieces. An upper parting bead is mounted on the jamb above the recess and the sash balance; a lower parting bead is 35 mounted on the jamb below the recess and the sash balance; and an intermediate parting bead spans the recess and the sash balance. This intermediate parting bead is removably attached to the jamb at positions above and below the recess and is held by the jamb in alignment 40 with the upper and lower lengths of parting bead to form a substantially continuous bead throughout the height of the window jamb.

The jamb of the window frame is ordinarily provided 45 with a groove in the exposed inside face of the jamb which receives the upper and lower parting beads. The ends of the intermediate parting beads are provided with means engaging this groove in order to align the intermediate section with the parting beads above and below. This aligning means ordinarily takes the form of a lug 50 or projection at each end of the intermediate section which is received within the groove, the central portion of the intermediate parting bead being, in effect, cut away at the underside so that it may rest against the sash balance at this cut away portion without projecting 55 farther outwardly beyond the jamb than the sections of parting bead above and below.

We show and describe the sash balance as being set 60 into the vertical side member of the window and the subdivided parting bead as being applied to this same side member of the frame, because this is the usual construction or relationship of these parts. However we are not necessarily limited to this position of the sash balance as balances may be placed in the horizontal head member, often termed the "head jamb" of the window frame. In this case, the head jamb also carries a similar parting bead which extends across the full width of the frame and lies against the inside of the upper sash. Our invention may also be used when the sash balance is in the head 65 above the sash. Consequently the term "jamb" as used herein is used in a generic sense to refer to either the side jamb or head jamb of a window frame.

How the above objects and advantages of our invention, as well as others not particularly mentioned herein, are attained will be better understood by reference to the following description and to the annexed drawings, in which: Fig. 1 is a fragmentary vertical section through the side jamb of a window frame, showing a frame and parting bead constructed according to our invention, a corner of each of the upper and lower sashes being included in the drawing;

Fig. 2 is a fragmentary elevation of the jamb of the window frame and the sash balance in the jamb, as viewed from the right of Fig. 1 with the sashes removed;

Fig. 3 is a vertical fragmentary section on line 3—3 of Fig. 2;

Fig. 4 is a perspective view of a preferred form of the intermediate section of the parting bead that spans the sash balance;

Fig. 5 is a fragmentary perspective of the upper end of the intermediate section of parting bead shown in Fig. 4;

Fig. 6 is a perspective similar to Fig. 4 showing a variational form of intermediate section of parting bead;

Fig. 7 is a fragmentary perspective view of the upper end of the parting bead of Fig. 6; and

Fig. 8 is a top end view of a sash balance with the intermediate section of the parting bead in cross-section showing a layer of sealing material between the parting bead and the face plate of the sash balance.

Referring now to the drawings, there is shown in Fig. 1 the side jamb of a window frame indicated generally at 10. It is the usual practice to cut in the side jamb a rectangular opening or recess 12 which is open to the exposed face 13 of the jamb and receives the spring-type sash balance indicated generally at 14. The sash balance is about the same thickness as the jamb and substantially fills recess 12. Sash balance 14 is mounted with its face plate 15 substantially flush with the exposed inside face 13 of jamb 10 over which the sashes slide. As may be seen from Fig. 1, face plate 15 extends for a short distance above and below recess 12 where it overlaps the window jamb. The sash balance may be fastened in place by any suitable means, as for example by nails 16 driven through the overlapping portion of the face plate and into the window jamb.

The details of construction of the sash balance are in no way limitative upon the present invention. The sash balance shown here is described more fully in the co-pending application of Axel W. Anderberg, Ser. No. 196,320, filed November 17, 1950 and which became Patent No. 2,644,193 on July 7, 1953 on "Spring Sash Balance" to which reference may be made for further details of its construction. In general, the sash balance is shown in Fig. 3 as including a pair of drums 18 each of which is rotatably mounted upon a fixed internal hub 19. Inside each drum is a spiral spring, not shown in the drawings, which connects the rotating drum to the fixed hub and tends to rotate the drum about the hub in a given direction. Wound around the outside of each drum 18 is a cable 20, the free end of which extends out of and below the sash balance as shown in Fig. 2. The lower end of each cable 20 is connected to one sash in any suitable way, as by a metal angle clip 22 which is firmly secured to the end of the cable. In Fig. 1, a clip 22 is shown fastened in place to the lower corner of upper sash 23. A similar clip, not shown in the drawings, is attached to the other cable 20 and fastened to the lower corner of lower sash 24. It will be seen from Fig. 1 that the two cables 20 extend downwardly from the sash balance between the face of jamb 10 and the sash to which they are each connected, there being sufficient clearance between the sashes and the jamb for this purpose. The two drums of the sash balance are enclosed by a housing or cover 25 which is secured to face plate 15 in any suitable manner.

Jamb 10 has in its exposed face 13 a longitudinally

extending groove 26 which extends for the full height of the jamb. In the side jamb as herein illustrated in Fig. 1, groove 26 is normally vertical. The purpose of this groove is to receive and hold the parting bead which, in the conventional construction, is a continuous member. According to our invention there is in groove 26 an upper parting bead 28 that extends upwardly from a point a short distance above the sash balance to the upper end of jamb 10. There is a similar lower parting bead 29 which extends downwardly from a point a short distance below the sash balance to the bottom of the jamb, the lower parting bead also being in groove 26. It is evident from Fig. 1 that groove 26 is interrupted by recess 12 and sash balance 14, which are normally located near or a short distance above the mid-point of the groove. To span recess 12 and the sash balance in it there is provided intermediate parting bead 30 which is physically separate from either the upper or lower parting bead. As will be described in greater detail, intermediate parting bead 30 is detachably fastened to jamb 10 at positions above and below recess 12 and sash balance 14 in a manner to hold it in alignment with the upper and lower parting beads in order to form with them a substantially continuous parting bead for the full height of jamb 10.

A preferred embodiment of the intermediate parting bead 30 is shown in Fig. 4. This intermediate parting bead is a hollow member formed from sheet metal bent to a generally U-shape in cross section. The transverse dimensions of parting bead 30 are designed to conform as closely as possible to the corresponding transverse dimensions of upper and lower parting beads 28 and 29 in order to provide in effect a continuous guide member with smooth sides against which the sashes may slide. Otherwise, the exact shape of the intermediate parting bead is immaterial. In each of several large areas in this country, parting beads are almost entirely of one size and shape. As between these various areas, however, these may be an appreciable variation in the dimensions of the parting bead which has become a standard in any one area. Consequently, no single size nor shape is contemplated for the intermediate parting bead since it is made to conform to the standard conventional parting bead above and below it.

Intermediate parting bead 30 is provided at each end with means for engaging the jamb of the window frame to establish and maintain the bead in the desired alignment with the bead above and below it. Such means is here shown as taking the form of two small lugs or projections 31 at each end of the parting bead. Projections 31 are designed to enter into groove 26, as may be seen in Figs. 1 and 3, and by engaging the sides of these grooves to align the intermediate parting bead with the upper and lower parting beads. The length of the projections or the overall width of parting bead 30 depends upon the corresponding width of the parting beads 28 and 29 as the intermediate bead preferably projects outwardly beyond the jamb the same distance as upper and lower beads 28 and 29.

With respect to projections 31 at each end of the intermediate parting bead 30, the central portion of the bead between these projections is recessed or cut back, reducing the net width of the bead. The edge surfaces 32 of the bead at this central recessed portion are preferably straight so that they can lie against and engage the exposed surface of face plate 15. In order to provide contact throughout the length of the sash balance, face plate 15 is preferably formed so that it has a substantially planar zone extending for the full length of the sash balance and located centrally of the balance in a position to be directly beneath parting bead 30. This planar zone may be wider than shown, but it has a width at least equal to the width of parting bead 30. The length of intermediate parting bead 30 is such that projections 31 enter groove 26 at locations immediately above and below

75 the sash balance. The intermediate parting bead spans

the entire sash balance and recess 12 in which the balance is located, and may be attached to the jamb by any suitable means. It is here shown as being fastened in place by nails 33 located one near each end of the parting bead so that there is one above and below the sash balance. Obviously, other fastening means such as screws or the like may be used. To facilitate the use of such fastening means, intermediate bead 30 is preferably provided at each end with a preformed hole 34, as shown in Fig. 5, to receive a nail or other similar fastening means. 10

For many installations, the fit between straight edges 32 of the intermediate parting bead and the exposed surface of face plate 15, especially when the latter is provided with a planar zone, is sufficiently close to prevent objectionable leakage of air between the parting bead and the face plate. However, if it is desired to eliminate all leakage at this point, weather stripping means, such as a thin sealing layer 36, shown in Fig. 8, may be inserted between the face plate and the parting bead. This layer of sealing material may be of any suitable material, for example felt, suitably treated paper, or the like. This weather stripping may be separate or attached to the face plate or the parting bead, and if the latter, may be considered to be a part of the plate or bead.

A variational form of intermediate parting bead is illustrated in Figs. 6 and 7. In this embodiment, parting bead 40 is a solid member provided at each end with a single solid projecting block 41 which is adapted to enter into groove 26 in the window frame for purposes as described. Over the central portion of the parting bead between these two terminal projections, the parting bead has a flat undersurface 42 which is adapted to engage the outer surface of face plate 15 of the sash balance. It is preferable that the intermediate parting bead be provided near each end with a preformed hole 44 adapted to receive a nail or a screw or other fastening means by which the intermediate parting bead is fastened to window jamb 10 above and below the sash balance. Except for the fact that this type of member is solid, rather than hollow as shown in Figs. 4 and 5, the external shape and various dimensions are unchanged from the above description. This intermediate parting bead may be made of any suitable material. For example, it may be molded from a suitable synthetic resin or plastic or may be pre-cut from wood.

A window frame construction according to our novel design has several advantages. It is easier and quicker to install the sliding sash since the operation of notching the parting bead is entirely eliminated and there is no problem of cutting and fitting when intermediate parting beads as shown in Figs. 4 or 6 are preformed. There is no problem of air leakage since air passing the intermediate parting bead may be practically eliminated by the use of a weather stripping layer as shown in Fig. 8.

One of the chief advantages of our improved construction is the ease with which a sash balance 14 can be removed from the frame for any desired purpose. The upper end of the intermediate parting bead is normally exposed so that the nail holding it in place can easily be removed; and by manipulating the sash the lower end may be made accessible for the removal of the nail at that end. With the fastening means taken out, the intermediate parting bead can be withdrawn from groove 26. Then by removing nails 16, the sash balance is unfastened from the jamb of the window frame. By tilting the upper end of the sash balance forwardly or inwardly of the frame and then lifting it up to remove the lower end from between the jamb and the sash, the sash balance may be removed easily and completely from recess 12. There is ordinarily enough clearance between each sash and the jamb to remove each cable 22 by pulling it forwardly from between the jamb and the sash. If desired, in order to facilitate removal of these cables from the inside of the window, the lower sash may be raised as far as it will go and the lower parting bead 29 removed

from groove 26. This makes it easier to pull cables 20 out from between each sash and the jamb or to replace them as the case may be.

From the foregoing it will be apparent that there may be variations of our invention thought of by persons skilled in the art yet which are within the spirit and scope of our invention. Consequently, the above description is considered as being illustrative of, rather than limitative upon, the appended claims.

We claim:

1. In a window frame for sliding sash having a recess in a jamb adapted to receive a spring-type sash balance set into the recess with its exposed surface substantially flush with the exposed surface of the jamb, the combination comprising: an upper parting bead extending upwardly from adjacent the sash balance and mounted on the jamb; a lower parting bead extending downwardly from adjacent the sash balance and mounted on the jamb, the spacing between the upper and lower parting beads being greater than the corresponding dimension of the sash balance; a separate intermediate parting bead spanning the recess and the sash balance to fill the gap between the upper and lower parting beads, said intermediate parting bead being in alignment with the upper and lower parting beads to form therewith, a substantially continuous parting bead structure; and means attaching said intermediate section to the jamb at positions above and below the recess in the jamb.
2. A window frame as in claim 1 in which the central portion of the intermediate parting bead is cut away at the under side to substantially the level of the surface of the jamb to engage the surface of the sash balance.
3. In a window frame for sliding sash having in one jamb a recess for receiving a sash balance and a groove extending longitudinally of the sash upwardly and downwardly from opposite sides of the recess, the combination comprising: an upper parting bead mounted on the jamb in the groove above the recess; a lower parting bead mounted on the jamb in the groove below the recess; a separate intermediate parting bead at the recess and in alignment with the upper and lower beads to form therewith a substantially continuous parting bead structure; and fastening means attached to the intermediate section at positions above and below the recess.
4. A window frame as in claim 3 in which the intermediate parting bead is provided at each end at positions beyond the sash balance with means fitting into the groove in the jamb to attach the parting bead thereto and to maintain the desired alignment of the intermediate parting bead.
5. A window frame as in claim 3 in which the central portion of the intermediate parting bead has on the under side recessed surfaces adapted to engage the sash balance over a planar zone for substantially the full length of the sash balance.
6. A window frame as in claim 3 in which the intermediate parting bead is a hollow metal member of generally U-shaped cross section having at each end projecting portions adapted to fit into the groove in the jamb to establish and maintain the desired alignment of the intermediate parting bead.
7. A window frame as in claim 3 which also includes a layer of sealing material between the intermediate parting bead and the sash balance.
8. In a window frame for sliding sash having a recess in one jamb adapted to receive a spring-type sash balance set into the recess, said jamb also having a groove extending upwardly from one side of the recess and downwardly from the opposite side of the recess, the combination comprising: an upper parting bead mounted on the jamb in the groove and extending upwardly from adjacent the sash balance; a lower parting bead mounted on the jamb in the groove and extending downwardly from adjacent the sash balance; closure means spanning the sash balance in engagement with the exposed surface.

of the sash balance and substantially filling the space between the ends of the upper and lower parting beads; and fastening means attached to the closure means at positions adjacent the ends of the closure means to hold the closure means in substantial continuation of and in alignment with the upper and lower parting beads.

9. A sash balance and parting bead construction for mounting on a window frame having a recess and a groove above and below the recess for receiving sections of a parting bead, comprising: a spring-type sash balance adapted to be set into said recess in the window frame with the exposed outer surface of the balance substantially flush with the exposed outer surface of the frame; and an intermediate section of parting bead having a relatively narrow, elongated body provided at each end with a laterally projecting portion adapted to fit within said groove in the window frame at positions above and below the sash balance, the projecting portions being spaced apart at least a distance equal to the corresponding dimension of the sash balance, the intermediate section of parting bead being of such dimensions as to form a substantial continuation of the sections of parting bead in the groove above and below the sash balance when the underside of the intermediate section of parting bead is closely adjacent said outer exposed surface of the balance.

10. The sash balance and parting bead construction as in claim 9 in which the intermediate section of parting bead is a hollow, sheet metal member of U-shaped cross-section.

11. As an article of manufacture, an intermediate section of parting bead for use in a window frame having a recess for receiving a spring-type sash balance set into the frame with its exposed outer face substantially flush with the exposed outer face of the frame, said frame having a groove above and below the recess to receive

30
35

other sections of parting bead, comprising: a relatively narrow elongated body provided at each end with a laterally projecting portion adapted to fit within said groove in the window frame, the projections being spaced apart longitudinally of the intermediate section at least a distance equal to the corresponding length of the sash balance, the intermediate section of parting bead being of such external dimensions as to form substantial continuations of parting bead sections in the groove above and below the sash balance.

12. As an article of manufacture, an intermediate section of parting bead for use in a window frame having a recess for receiving a spring-type sash balance set into the frame with its exposed outer face substantially flush with the exposed outer face of the frame, said frame having a groove above and below the recess to receive other sections of parting bead, comprising: a relatively narrow elongated body provided at each end with a laterally projecting portion adapted to fit within said groove in the window frame, the projections being spaced apart longitudinally of the intermediate section at least a distance equal to the corresponding length of the sash balance, the intermediate section of parting bead being of such external dimensions as to form substantial continuations of parting bead sections in the groove above and below the sash balance, the intermediate section of parting bead being a hollow sheet metal member of U-shaped cross-section.
